VARIABLE RESISTOR ADJUSTABLE ELECTRICAL INSTRUMENTS

Marlan E. Bourns, Riverside, Calif., and Richard E. Caddock, Ames, Iowa; said Caddock assignor to Bourns Laboratories, Inc., a corporation of California

Application May 2, 1957, Serial No. 656,556

1 Claim. (Cl. 201—56)

This invention relates to new and improved adjustable electrical instruments, and more particularly to adjustable electrical instruments such as potentiometers which are specifically designed so as to be capable of being used in very small devices such as, for example, hearing aids.

The past several years have seen a very drastic change in the design of hearing aids. Formerly conventional hearing aids were comparatively bulky structures which had to be carried in some sort of a pocket or other receptacle upon the clothing of an individual. The advent of transistors and transistorized circuits has made possible a very definite reduction in size in hearing aids. Commonly at the present time the principal operative parts of a hearing aid are disposed in extremely small containers or in parts of glasses or the like so that they may be conveniently worn by an individual.

Potentiometers are used in hearing aids in order to vary the volume level of sound produced. In general terms, it may be concluded that potentiometer development has not kept pace with the development of hearing aids since hearing aids commonly marketed at the present time use essentially the same type of potentiometers formerly employed. A common type of rotary potentiometer used for volume control in many hearing aids at the present time is about $\frac{5}{8}$ " to $\frac{3}{4}$ " in diameter, and is approximately $\frac{1}{4}$ " thick. Obviously this size is inconvenient for many of the present applications. Also conventional potentiometers such as rotary potentiometers used with hearing aids are objectionable because of the knob-type arrangements used for adjusting these instruments and because of certain other structural details. In general the very prior potentiometers tend to be "noisy" because of a number of reasons such as reasons related to the type of resistance elements utilized and because of other structural details.

A broad object of the present invention is to produce new and improved potentiometers which are specifically adapted for use with hearing aids and other types of similar devices. Another object of the present invention is to provide potentiometers of this category which include a switch mechanism carried by and actuated by parts of these instruments. A still further object of the present invention is to provide new and improved potentiometers which are extremely reliable in use and which may be easily and comparatively inexpensively constructed.

Another extremely important object of the present invention is to provide potentiometers which can be formed in a variety of different manners so as to provide for linear or non-linear or functional adjustment of electrical values, during adjustment of these instruments in a uniform or "linear" manner. Thus, for example, it is possible to provide hearing aid potentiometers achieving functional outputs corresponding to the so-called "audio-taper." This term is commonly used in the hearing aid field to designate a certain type of volume control. Another object of the present invention is to provide potentiometers for hearing aid and other uses which overcome many of the other disadvantages and limitations of

2

conventional hearing aid and other potentiometers as indicated broadly in the preceding discussion.

Still further objects of the invention as well as many specific advantages of it will be more fully apparent to those skilled in the art to which this invention pertains from a detailed consideration of the remainder of this specification including the appended claim and the accompanying drawing in which:

Fig. 1 is a perspective view of a potentiometer of this invention;

Fig. 2 is a cross-sectional view taken at line 2—2 of Fig. 1;

Fig. 3 is a cross-sectional view taken at line 3—3 of Fig. 2;

Fig. 4 is a cross-sectional view taken at line 4—4 of Fig. 2; and

Fig. 5 is an exploded perspective view of the potentiometer showing in Fig. 1.

It is to be understood that the accompanying drawing is not to be taken as limiting this invention in any respect. This drawing is primarily intended so as to clearly indicate the nature of a presently preferred embodiment of the invention. Because of the purpose of the drawing it does not represent any precise commercial unit drawn to scale. Obviously instruments falling within the scope of this invention having a different appearance may be manufactured by altering a number of structural details without departing from the essential features of the invention as herein explained.

As an aid to the understanding this invention it may be stated in essentially summary form that it involves adjustable electrical instruments such as potentiometers, each of which is built to include a resistance element disposed upon a non-conductive member in such a manner that portions of the resistance element along its length extend in a curved path from and around the non-conductive member and from the rest of the resistance element. With the invention a contact member is rotatably mounted adjacent to such a resistance element, and curved contact means extending around the resistance element are provided so as to engage different parts of these projecting portions of the resistance element as during movement of the contact member so as to adjust an electrical value. Constructions of this category differ from a number of different prior constructions in that a definite curved "path" or line for electrical contact between the parts is provided on both the resistance element and the contact member for use establishing electrical communication between these two operative parts.

The actual details of this invention are best more fully explained by referring directly to the accompanying drawing. In Fig. 1 there is shown a perspective view of a complete hearing aid potentiometer 10 of the present invention which is built so as to include end caps 12 between which there is rotatably held a non-conductive cylindrical housing 14. If desired the exterior of this housing may be knurled or serrated so as to aid in the adjustment of the potentiometer 10. Preferably the end caps 12 are each formed out of a non-conductive material such as an appropriate phenolic resin so as to each include a flat bottom surface 16 which is adapted to rest upon appropriate mounting surface (not shown) such as a printed circuit terminal board. Within the center of each of these end caps 12 there are provided openings 18 which are adapted to hold nail-like fasteners 20.

As indicated in Fig. 2 of the drawing the fasteners extend from the openings 18 into a central opening 22 in a cylindrical non-conductive member 24 and serve to hold this non-conductive member 24 within interior cavities 26 formed in opposed sides of the end caps 12 so as to space these end caps from one another. As is best indicated in Fig. 2 of the drawings the non-conductive member 24 in-

cludes a ridge 28 formed around the exterior thereof between the end caps 12. Preferably this ridge 28 is molded integrally with the member 24, although if desired, it may take the form of a simple non-conductive wire secured to the exterior of the member 24 by conventional means such as, for example, ends of such a wire fitting within holes in this member 24. Preferably the edge of the ridge 28 furthest removed from the member 24 should be accurately formed so that this edge is always spaced at a given distance from the axis of the housing 14 in order to insure proper operation of the potentiometer 10.

Around the exterior of the member 24 and the ridge 28 there is located a wound resistance element 30 which is preferably formed of comparatively fine, accurately dimensioned wire such as, for example appropriate Ni-chrome wire. The ends of this resistance element are attached to wire terminals 32 which, as shown in Fig. 2 of the drawing, fit within grooves 34 in the member 24 beneath ends of the element 30 and which extend from these grooves 34 through appropriate openings 36 in the end caps 12. The resistance element 30 may be attached to the terminals 32 by various conventional means such as by the use of solder.

On the interior of the housing 14 there is formed an elongated projection 38 which is adapted to fit within notches 40 in the ends 42 of a contact member 44. As is best seen in Fig. 5 of the drawings these ends 42 each have the essential shape of a washer, and these ends are connected by means of a wall 46 which fits closely against the interior of the housing 14. Between the ends 42 there extends a resilient metal contact element 48 having essentially a U-shape as indicated in Fig. 2 of the drawings. This contact element 48 is connected to both the ends 42; further, the wall 46 is attached to it in order to give the contact element 48 sufficient rigidity so that the satisfactory operation of the potentiometer 10 may be achieved. Preferably the contact member 44 is formed of a resilient metal.

A bowed spring-like washer 52 is located within one of the cavities 26 in one of the end caps 12 so as to resiliently bear against one of the ends 42 of the contact member 44 as indicated in Fig. 2 of the drawings. Another wire-like terminal 54 of metal having a bent configuration as illustrated is attached to a portion of the washer 52 as by welding or other equivalent techniques so as to extend from it through openings 56 in one of the end caps 12. This terminal 54 serves as an electrical return terminal for the complete potentiometer 10. It will be realized that as the housing 14 is turned the contact element 48 will engage different parts or portions of the portion of the resistance element 30 carried upon the ridge 28 so as to establish electrical communication therewith. Thus, the potentiometer 10 may be adjusted by simple turning of the housing 14.

Within this potentiometer 10 it is preferred to incorporate a switch mechanism 58 of the type indicated in Fig. 4 of the drawing. As illustrated openings 60 are provided within an end cap 12 as to carry parts of the switch terminals 62 and 64. These switch terminals end within the cavity 26 in this end cap 12. The terminal 62 is located so as to fit within an apex or bent portion 64 of a resilient metal switch arm 66 having sides 67 and 69. This switch arm is formed so that the side 67 is held against the interior of the cavity 26 at all times and so that the side 69 is held against the other terminal 64 by means of the exterior of a rotary actuator 68 bearing against a small bent projection 70 formed in the side 69. The actuator 68 is preferably formed of appropriate non-conductive material such as, for example, a phenolic composition so as to fit within the cavity 26 in this end cap 24 and so as to partially fit within an end of the housing 14. It (the actuator 68) includes a notch 72 which is engaged by the projection 38 formed upon the interior of the housing 14 so as to be capable of rotation therewith. Another notch 74 in the exterior of the ac-

tuator 68 is adapted to receive the projection 70 during rotation of the housing 14 so as to permit the side 69 of the switch arm 66 to move with essentially a "snap action" in order to break contact between the terminals 62 and 64 in the obvious manner. Further rotation of the housing 14 of course forces the projection 70 from the notch 74 so as to re-establish contact between these terminals 62 and 64.

An important feature of this invention lies in the fact that both the ridge 28 and the contact element 48 extend around the axis of the potentiometer 10 in a curved path of less than 360° of a circle. Thus, it is impossible with the construction shown for the contact element 48 to engage the resistance element 30 at more than a single point at any one time as the potentiometer 10 is operated. Also, the switch mechanism may be formed so as to be automatically "shut off" when the contact element 48 is not engaging the resistance element 30.

As previously indicated during the use of this potentiometer, the housing 14 is rotated and such rotation causes the contact element 48 to engage different portions of the resistance element 30 overlaying the ridge 28. Those skilled in the art to which this invention pertains will realize that the curved paths of both the ridge 28 and the contact element 48 around the axis of the potentiometer 10 permit a degree or type of adjustment which cannot be obtained with conventional constructions.

As an example of this, it is necessary to refer in more detail to the operation of the potentiometer 10. It is possible to form the curved paths defined by the ridge 28 and the contact element 48 in various manners so that a given amount of rotation of the housing 14 starting from various positions in which the housing 14 may be located will not produce a corresponding uniform adjustment of an electrical value. Thus, it is possible to provide within the scope of this invention constructions in which rotation of the housing 14 at a uniform rate causes adjustment of the potentiometer 10 in accordance with the so-called audio-taper. In essence what is involved is a "double" functional operation since both the ridge 28 and the contact element 48 extend in curved paths around the axis of the entire instrument and since both of these paths may be designed so as to each provide for a functional adjustment of the entire potentiometer 10. When so constructed instruments of this invention may be rapidly adjusted by a comparatively small amount of rotation of the housings employed.

A number of different types of switch mechanisms may be incorporated with potentiometers falling within the broad scope of this invention. The particular switch mechanism shown and described is considered to be especially adapted for use with instruments of this invention in view of the assembly employed for this switch mechanism and in view of the fact that the operative parts of it may be carried within or upon other parts of the instrument of the invention without any material change in the size of these parts. The particular switch mechanism shown is also considered advantageous inasmuch as it is simple and provides an effective "snap action" such as is very desirable for hearing aids.

Obviously a wide variety of different modifications may be made in the instrument shown without departing from the essential features or principles of this invention. As an example of such modification these instruments can be employed as variable resistors by simply omitting one of the terminals connected to one of the ends of the resistance element employed in any unit. Further, various equivalent resistance elements can be employed, and various other means than are shown can be employed for attaching the end caps to other parts in assembly. Also it is obviously possible to omit the switch mechanism shown although this is not considered desirable from commercial and utilitarian reasons. For these reasons this invention is to be considered as being limited only

by the appended claim, and the claim is to be interpreted in the light of patent doctrine of equivalents.

This application is a continuation-in-part of the pending application entitled Adjustable Resistors, Serial No. 598,284, filed July 17, 1956.

We claim:

A variable resistor comprising a pair of spaced apart end caps having a cylindrical mandrel extending between them, said mandrel having a helical ridge formed thereon, resistance wire wrapped around said mandrel and over said helical ridge, a tubular sleeve rotatably mounted on said end caps and enclosing said mandrel, said sleeve having a spiral contact element disposed to wipe on said resistance wire where the latter passes over helical ridge, a stationary washer of conductive material engaging one end of said contact element, and terminal means con-

nected to said washer and to the ends of said resistance wire, said terminal means passing out of said variable resistor through said end caps.
